UNITED STATES PATENT OFFICE.

ARTHUR TREVOR DAWSON AND GEORGE THOMAS BUCKHAM, OF LONDON, ENGLAND,
ASSIGNORS TO VICKERS LIMITED, OF WESTMINSTER, ENGLAND.

AUTOMATIC GUN MOUNTING.

1,110,257.

Specification of Letters Patent. Patented Sept. 8, 1914.

Application filed February 20, 1914. Serial No. 819,864.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Automatic Gun Mountings, of which the following is a specification.

This invention relates to automatic gun mountings and has for its chief object to so construct the mounting that the gun can at will be converted from one for firing at the usual small maximum angle of elevation to one capable of being elevated to a high maximum angle for use in firing at aeroplanes or other aerial vessels.

According to this invention we provide means whereby, in the case of a tripod mounting, the gun can be moved about an approximately vertical axis through an angle of 180 degrees so that the rear end of the gun is contiguous to the front legs of the mounting, the gun being then capable of being elevated by its handle block through large angles. In the case of a pedestal or naval mounting the top carriage is mounted on curved vertical guides and is clamped thereto when the gun is to be elevated through the usual small angles, but can be unclamped so that the said top carriage together with the gun can be moved by hand upon the curved guides through large angles of elevation.

In order that the said invention may be clearly understood and readily carried into effect, we will describe the same more fully with reference to the accompanying drawings in which:—

Figures 1, 2 and 3 are side elevations showing a tripod mounting constructed in accordance with our invention the gun being depicted in different positions relatively to the mounting. Fig. 4 is a rear elevation of Fig. 1. Fig. 5 is a side elevation viewed from the opposite side to that of Fig. 3, showing on a larger scale important features of our constructional form of the invention, the gun being adjusted to the position shown in Fig. 3 for firing at high angles of elevation. Fig. 6 is a view similar to Fig. 5 (but with some of the parts omitted) showing the position of the parts when the gun is in the position illustrated in Fig. 1. Figs. 7 and 8

are vertical sections taken on the lines 1—1 and 2—2 of Figs. 5 and 6 respectively. Figs. 9, 10 and 11 are respectively a side elevation, a rear elevation and a plan (the latter with the gun removed) of a pedestal or naval mounting constructed in accordance with our invention.

In all these figures, A is the gun and A' the gun trunnion pin. B is the crosshead in which the gun is mounted and B' the elevating gear for the gun.

Referring more particularly to Figs. 1 to 8, the frame C that carries the front legs C', C' and the trail C², is formed with a curved guide c disposed in a vertical plane 70 and upon which a sliding plate C³ is capable of moving, the said plate being made integral with the training arc c' and with the socket c² for the training pivot b of the cross-head B in which the gun is trunnioned. 75 The said sliding plate C³ is provided with an eccentric clamping device c³ for retaining it in any required position on the guide c.

The crosshead B instead of being rigidly connected to or made integral with the rearwardly extending arm B^x carrying the elevating gear B' and engaging with the training arc c', is connected to the said arm through the intervention of a clamping device in such a manner that relative movement can at will be caused to take place between the crosshead and the said arm. This clamping device may comprise, as shown, a screw threaded stud b² carried by a socket B² forming part of the arm B^x. This stud 80 has a handle b^{2x} by means of which it can be moved into or out of engagement with the crosshead B.

When the gun is being elevated in the ordinary way by the elevating gear B' the clamping stud b² is in the engaging position shown in Fig. 8—that is to say the crosshead B and the rearwardly extending arm B^x are locked together—training being effected in the usual manner by moving the 95 said arm on its training arc c'. When it is desired to fire at high angles of elevation, the clamping stud is moved out of engagement with the crosshead (Fig. 7), the elevating screw is liberated, and the gun and its crosshead are swung relatively to the rearwardly extending arm B^x about the training pivot b so that the rear of the gun is contiguous to the front legs C' C' of the tripod as shown in Figs. 3 and 5. The gun 100

110

can then be elevated to almost a vertical position (75°) without impediment, the rear of the gun being then disposed between the front legs of the tripod. It will be obvious 5 that this high angle of elevation could not be obtained with the gun in its usual position, since the rear end of the gun would foul the trail C^2 of the tripod. The aforesaid curved guide c has an arc 10 somewhat greater than that of a semi-circle, so that the training pivot b can be adjusted to the vertical position notwithstanding large variations in the inclination of the ground upon which the tripod rests (see 15 Fig. 2).

Referring to Figs. 9 to 11, the pedestal D is provided with a fixed training plate d which is circular in plan, and is adapted to be engaged by detachable clips d' carried 20 by a bracket D' which is formed with a socket to receive the training pivot d'' carried by the training plate d . This bracket is provided with vertically arranged semi-circular guides d''' upon which the top carriage or crosshead B is mounted. This top carriage is forked to receive the trunnion pin A' . The top carriage also carries the usual elevating screw B' and a clamp d^2 for retaining the top carriage in the required 25 position. This clamp is normally in the engaging position, and the gun is then elevated by the said screw. When it is desired to elevate the gun to a high angle, the clamp is released and the top carriage is moved 30 around the guides d''' on the aforesaid bracket D' . A suitable clamp D'' may be provided for co-operating with the training socket and the pivot d'' to retain the gun in any desired position of training.

40 Each of the herein described constructions of gun mounting may be provided with a cartridge belt box E similar to that set forth in our applications for British Patent No. 3552 of 1913 and No. 378 of 1914. In 45 the construction shown by Figs. 9 to 11 however the belt box is shown as being fixed to the bracket D' .

What we claim and desire to secure by Letters Patent of the United States is:—

50 1. In a tripod gun mounting, the combination with the front legs and trail thereof, the member to which said legs and trail are connected, the crosshead in which the gun is trunnioned, and the member carrying the 55 elevating gear, of means for enabling the crosshead to be moved relatively to said second member through an angle of 180 degrees to bring the rear end of the gun contiguous to the said front legs for enabling 60 the gun to be elevated through large angles with the rear end of the mechanism casing between the front legs.

2. In a tripod gun mounting, the combination with the front legs and the trail 65 thereof and the casing to which said legs

and trail are connected, of a curved guide on said casing, a sliding member mounted on said guide, a socket forming part of said member, a crosshead in which the gun is trunnioned, a training pivot on said crosshead, and means for enabling said crosshead and the gun to be moved about said pivot through an angle of 180 degrees to bring the rear end of the gun contiguous to the said front legs and thereby enable the 75 gun to be elevated through large angles with the rear end of the mechanism casing between the front legs.

3. In a tripod gun mounting, the combination with the front legs and the trail 80 thereof and the casing to which said legs and trail are connected, of a curved guide on said casing, a sliding member mounted on said guide, a training arc carried by said member, a crosshead in which the gun is trunnioned, a rearwardly extending arm engaging with said training arc, elevating gear carried by said arm and clamping means between said crosshead and said arm for at 85 will holding said parts rigid with one another or enabling the crosshead to be moved in an approximately horizontal plane through an angle of 180 degrees to bring the rear end of the gun contiguous to the said front legs and thereby enable the gun to be 90 elevated through large angles with the rear end of the mechanism casing between the front legs.

4. In a tripod gun mounting, the combination with the front legs and the trail 100 thereof and the casing to which said legs and trail are connected, of a curved guide on said casing, a sliding member mounted on said guide, a training arc carried by said member, a socket forming part of said member, a crosshead in which the gun is trunnioned, a rearwardly extending arm engaging with said training arc, a training pivot on said crosshead disposed in said socket, elevating gear carried by said arm and 110 clamping means between said crosshead and said arm for at will holding said parts rigid with one another or enabling the crosshead to be moved about said training pivot through an angle of 180 degrees to bring the 115 rear end of the gun contiguous to the said front legs and thereby enable the gun to be elevated through large angles, with the rear end of the mechanism casing between the front legs.

5. In a tripod gun mounting, the combination with the front legs and the trail thereof and the casing to which said legs and trail are connected, of a curved guide on said casing, a sliding member mounted on said guide, a training arc carried by said member, a socket forming part of said member, a crosshead in which the gun is trunnioned, a rearwardly extending arm engaging with said training arc, a training pivot 125 130

on said crosshead disposed in said socket, elevating gear carried by said arm, a clamping screw carried by said arm for engagement with the crosshead, said screw when 5 in the disengaged position enabling the crosshead and the gun to be moved about the training pivot through an angle of 180 degrees to bring the rear end of the gun contiguous to the front legs of the tripod and 10 thereby enable the gun to be elevated

through large angles with the rear end of the mechanism casing between the front legs.

In testimony whereof we affix our signatures in the presence of two witnesses.

ARTHUR TREVOR DAWSON.
GEORGE THOMAS BUCKHAM.
